Specification for Design.

Patented Apr. 26, 1921.

Application filed September 11, 1920. Serial No. 409,713. Term of patent 14 years.

To all whom it may concern:

Be it known that I, WILLIAM J. HINES, a subject of the King of Great Britain, and a resident of Hartford, in the county of Hartford and State of Connecticut, have invented a new, original, and ornamental Design for Sink-Scrapers, of which the following is a specification, reference being had to the accompanying drawings, forming part thereof, in which—

Figure 1 is a front view of a sink scraper embodying my invention.

Fig. 2 is an end view of the same.

Fig. 3 is an edge view of the same.

Fig. 4 is a view in lengthwise section through the same.

Fig. 5 is a view in cross section through the same.

I claim:

The ornamental design for a sink scraper, as shown.

WILLIAM J. HINES.
